FOUNTAIN PEN

Edward F. L. Michael, New York, N. Y., assignor
of one-half to Max Grill, New York, N. Y.

Application October 19, 1935, Serial No. 45,767

7 Claims. (Cl. 120—42)

This invention relates to new and useful improvements in fountain pens and more particularly it pertains to fountain pens of the type which employ more than one color of ink and which are capable of writing at will with any of the particular colors of ink.

It is an object of the invention to provide a fountain pen in which at least two different colors of ink may be employed and in which either color may be used independently of the other color.

A further object of the invention resides in a new and novel construction and arrangement of parts whereby the inks are maintained separately at all times with no possibility of their intermingling.

Still a further object of the invention resides in a novel construction of filling means whereby the ink reservoir may be independently filled by a mechanism which may be independently connected with each reservoir for operation.

With the above and other objects in view, reference is had to the accompanying drawing, wherein:

Figure 1 represents in elevation, a pen constructed in accordance with the present invention,

Figure 2 is an enlarged longitudinal sectional view with parts broken away taken substantially on the line 2—2 of Figure 1,

Figure 3 is a transverse sectional view taken substantially on the line 3—3 of Figure 1,

Figure 4 is a transverse sectional view taken substantially on the line 4—4 of Figure 2,

Figure 5 is a transverse sectional view taken substantially on the line 5—5 of Figure 2,

Figure 6 is a transverse sectional view on an enlarged scale taken substantially on the line 6—6 of Figure 2,

Figure 7 is a detail view in elevation on an enlarged scale illustrating the method in which the pen points or nibs are operated in order to be moved to either of their operative positions, and;

Figure 8 is a distended perspective view with a portion of the barrel broken away.

Referring more particularly to the drawing, the pen comprises a barrel section 10, which barrel section 10 is divided longitudinally by a partition 11 to form two ink reservoirs 12 and 13. The rear end of the barrel section is closed by a wall 14 which has two passages 15 and 16 therethrough. The forward end of the barrel 10 is closed by a wall 19, and passing therethrough there are two tubular members 17 and 18 which extend to a point closely adjacent the rear wall

14 of the barrel 10. When the parts are in their assembled position, the tubular member 17 will be substantially in line with the passage 15 and the tubular member 18 will be substantially in line with the passage 16 of the wall 14, and the upper end of each of these tubes is flared as at 20. The purpose of this construction will be hereinafter described.

Carried by the forward end of the tube 17, there is a semi-circular tubular member 22, and carried by the forward end of the tube 18, there is a similar member 23. These members are spaced with respect to each other, as illustrated in Figure 4, and as best illustrated in said figure, the tubular members 17 and 18 are of such diameter as to form a tight friction fit between the curved wall and the straight wall of their respective forward tubular member 22 or 23 where they are engaged therewith. This construction provides spaces 24 upon opposite sides of the tubular members 17 and 18 through which the ink may flow from the reservoirs 12 and 13 into the forward tubular members 22 and 23, respectively.

As best illustrated in Figure 2, the tubular members 17 and 18 terminate at a point short of the forward end of their respective tubular members 22 and 23, as illustrated at 26 in Figure 2, and this construction provides a relatively small space 27 between the ends of the tubular members 17 and 18 and the forward ends of their respective tubular members 22 and 23.

Carried by the tubular extensions 22 and 23, there is a sleeve member 30, best illustrated in Figures 6 and 8. This sleeve member is cut out as at 31 and 32 to provide leg extensions 33 which are spaced from each other. This sleeve is of such a diameter that it has a friction fit with the tubular members 22 and 23, which friction fit will be sufficient to retain it in either of the adjusted positions to which it is moved and which will be hereinafter described.

The writing nibs or points are designated 40 and 40' and they are carried by a block 41, which block 41 has two angularly disposed passages 42 and 43 which lead respectively to the feed bars 44 and 45 of the writing nibs or points 40 and 40'. Each of these passages 42 and 43 terminates in a nipple 46, and these nipples 46 are adapted to be received in openings 47 in the inner flat faces 48 of the leg extensions 22 and 23, this construction being shown in Figure 8. The marginal edges of the openings 47 are flanged, as best illustrated at 49 in Figure 6, and the nipples 46, heretofore mentioned, cooperating

with the flanged edge of their respective openings 47 form a liquid tight joint between the block 41 and the tubular leg extensions 22 and 23, thus assuring that there is no leakage of ink at this point. In addition to providing a liquid tight joint, the construction just described provides for pivotally mounting the block 41 between the leg extensions 22 and 23 in order that the same may be rotated between the legs to 10 move the writing nibs or points into and out of operative writing position, as illustrated by dotted and full line positions in Figure 7 of the drawing.

With the parts in the position in which they are shown in Figure 2, ink will feed from the reservoir 13 to the tubular leg 23, from which it will pass through the passage 43 to the feed bar 45 of the writing nib or point 40'. If, however, the block 41 be rotated through 180°, the feed bar 44 would then be moved to the forward position and the ink would feed from the reservoir 12 to the tubular leg extension 22 through the passage 42 to the feed bar 44 of the other writing nib or point 40.

25 The reference numeral 50 designates a bolt which is threaded as at 51 into a bushing carried by the rear wall 14 and rotatably mounted upon this bolt 50 there is a disk like member 52 which has a passage 53 therein. This passage 30 53 is adapted to be brought into registration with either of the passages 15 and 16 for a purpose to be now described. The member 52 has an extension 54 which carries a compressible sack 55 which is adapted when collapsed and allowed to 35 refill, to draw ink into either of the reservoirs 12 or 13 as the case may be. With the parts in the position in which they are shown in Figure 2, if the feed bar 45 be submerged in a receptacle of ink and the sack 55 collapsed, air will 40 be forced from the sack 55 through the passages 53 and 16, the reservoir 13, tubular member 18, passage 43, and in this manner discharged from the pen. Upon release of the collapsible sack 55, ink will be drawn in through the feed bar, 45 passage 43, and into the tubular leg extension 23. A few such operations will completely fill the reservoir with ink, after which the member 52 is rotated so that its passage 53 will be out of registration with the passage 51. Registration 50 of the passage 53 with the passage 15 and operation as just described will fill the reservoir 12 with ink which obviously, would be of a different color. The member 52 may be provided with suitable indicating means in the form of a notch 58 adapted to register with notches 59 upon the extension 60 of the barrel 10 in order to indicate the proper position of the member 52 to have its passage 53 register with either the passage 15 or 16. A suitable cap 61 may have 55 threaded engagement with the barrel 10 as at 62 to enclose the collapsible member when the same is not in use, and a reversible cap 63 which carries the conventional pocket clip 64 is adapted 60 for threaded engagement as at 65 of the barrel 10 in order to enclose the writing end of the pen when not in use.

In order to rotate the block 41 through 180° as heretofore described, the sleeve member 30, heretofore mentioned, must be turned until the 70 spaces 31 and 32 coincide with the space between the tubular leg extensions 22 and 23, in which position the block 41 is free to move through the spaces between the legs of the sleeve and the tubular members 22 and 23. After the 75 block has been rotated to the desired position to

expose either of the writing nibs or points, the sleeve 30 is again rotated so that its extensions 31 and 33 will cover or enclose the open spaces between the tubular extensions 22 and 23, as best illustrated in Figures 4 and 5, in which position the block 41 will be held against movement about its pivotal points, and the pen exposed for writing will be rigidly held in writing position.

5 In order to retain the member 52 tightly upon the wall 14, a washer 70 and a spring 71 may 10 be interposed between the head 72 of the bolt 50 and the upper face of the member 52. The bolt 50 being anchored in the wall 14, and the spring 71 being under compression, a tight working fit between the member 52 and the wall 14 15 will be had.

From the foregoing it will be apparent that the present invention provides a new and improved fountain pen in which at least two colors of writing fluid may be employed and in which the 20 choice of writing fluids may be made at will.

While the invention has been herein illustrated in its preferred form, it is understood that it is not to be limited to the specific details of construction herein shown and that it may be practiced in other forms which rightfully fall within the scope of the appended 25 claims.

Having thus described the invention, what is 30 claimed as new, is:

1. In a fountain pen, a barrel, a pair of tubular extensions projecting from the forward end of said barrel, a plurality of writing nibs or points rotatably mounted between the tubular extensions 35 whereby either of the writing nibs or points may be positioned for operation, and means for securing the writing nib or point adjusted for operation in its operative position, said last mentioned means embracing the tubular extensions 40 and having cut out portions adapted for registration with the spaces between the tubular extensions to permit of free rotary movement of the writing nibs or points.

2. In a fountain pen, a barrel, a pair of tubular extensions projecting from the forward end of 45 said barrel, a plurality of writing nibs or points rotatably mounted between the tubular extensions whereby either of the writing nibs or points may be positioned for operation, and means for securing the writing nib or point adjusted for operation in its operative position, said last mentioned 50 means comprising a sleeve embracing the tubular extensions, said sleeve having cut out portions being adapted for registration with the spaces between the tubular extensions when the sleeve is rotated to permit of free rotary movement of the writing nibs or points, and said leg extensions being adapted when the sleeve is rotated to close 55 the spaces between the tubular extensions and hold the writing nibs or points in their operative position.

3. In a fountain pen, a barrel, means for closing the forward and rear ends of the barrel, tubular 65 ink feeding extensions projecting from the closing means of the forward end of the barrel, and tubular members projecting through said tubular extensions and extending to a point closely adjacent the closing means of the rear end of the 70 barrel.

4. In a fountain pen, a barrel, means for closing the forward and rear ends of the barrel, tubular 75 ink feeding extensions projecting from the closing means of the forward end of the barrel, and

5 tubular members projecting through said tubular extensions and having their forward ends terminating at a point closely adjacent the forward ends of the tubular extensions and their rear ends terminating at a point closely adjacent the closing means of the rear end of the barrel.

5. In a fountain pen, a barrel, means for closing the forward and rear ends of the barrel, tubular ink feeding extensions projecting from the closing means of the forward end of the barrel, tubular members projecting through said tubular extensions and having their forward ends terminating at a point closely adjacent the forward ends of the tubular extensions and their rear ends terminating at a point closely adjacent the closing means of the rear end of the barrel, and a plurality of writing nibs or points carried by the tubular extensions, said writing nibs or points being movable selectively to operative position.

10 6. In a fountain pen, a barrel, means for closing the forward and rear ends of the barrel, tubular ink feeding extensions projecting from the closing means of the forward end of the barrel, tubular members projecting through said tubular extensions and having their forward ends terminating at a point closely adjacent the forward ends of

the tubular extensions and their rear ends terminating at a point closely adjacent the closing means of the rear end of the barrel, and a plurality of writing nibs or points carried by the tubular extensions, said writing nibs or points being rotatably mounted between the tubular extensions whereby they may be alternately moved to operative writing position.

15 7. In a fountain pen, a barrel, means for closing the forward and rear ends of the barrel, tubular ink feeding extensions projecting from the closing means of the forward end of the barrel, tubular members projecting through said tubular extensions and having their forward ends terminating at a point closely adjacent the forward ends of the tubular extensions and their rear ends terminating at a point closely adjacent the closing means of the rear end of the barrel, and a plurality of writing nibs or points carried by the tubular extensions, said writing nibs or points being rotatably mounted between the tubular extensions whereby they may be alternately moved to operative writing position, and means for establishing communication between each writing nib or point and one of said tubular extensions.
